many, a corporation of Germany

Application September 27, 1929, Serial No. 395,505
In Germany October 1, 1928

7 Claims. (Cl. 179—171)

The present invention is concerned with a method adapted to divide or split in a transmitter station a certain output radio frequency oscillation into two or more other oscillations (oscillation bands) of different frequencies, though substantially like amplitude, with the original carrier frequency being incidentally omitted.

The ensuing or final frequencies thus obtained, if they differ but comparatively little from each other or from one another, inter alia, may be employed also to advantage for the simultaneous transmission of one and the same communication, and this is particularly advisable in short-wave work for the purpose of overcoming the phenomena of fading.

For a better understanding of the idea underlying this invention and the operation of the circuits incorporating it reference may be had to the drawings, in which,

20 Figure 1 illustrates diagrammatically one embodiment of our invention;

Figure 2 illustrates by curves certain conditions existent in the circuits as employed:

25 Figure 3 illustrates our invention more completely;

Figure 4 illustrates a modification of our invention in which certain type of chokes are utilized;

Figure 5 illustrates a Wheatstone bridge arrangement for accomplishing the purpose of the invention;

30 Figure 6 illustrates a modification of the circuit shown in Figure 5; and,

Figures 7 to 10 inclusive illustrate the invention as applied to circuits without the need of 35 direct current being superimposed.

In Figure 1, it is assumed that the terminals pp from some suitable radio frequency generator are fed with radio frequency current $i_1 = J_1 \sin \omega_1 t$ whose amplitude is constant by the adoption of 40 means and ways later to be explained, i. e., independent of the impedances connected at the points aa or of the current there derived. Now, as shall hereinafter be demonstrated, it is possible to produce in the branch z two radio frequency oscillations of like amplitudes, though different frequencies if current in the parallel branch or shunt LC (which will hereinafter be referred to as a "coupler branch") is modulated in a certain way.

50 It shall be assumed that the inductance contained in the coupler branch is due to an iron-cored choke-coil whose reactance $\omega_1 L$ active in respect of the comparatively small radio frequency currents is acted upon both by a direct current i_g derived from a direct current source b

and a modulating current $i_m = J_m \sin \omega_m t$ produced by an alternating current generator d . Hence, through the winding e of the said iron-cored choke-coil there flows a resultant pulsating current $i_r = i_g + i_m$. The resultant reactance x_k of the coupler branch for the radio frequency ω_1 varies with i_r and i_m , respectively. Now, the parts of the said branch are chosen in such a way that its resultant reactance x_k active for the radio frequency ω_1 disappears simultaneously with the modulator current i_m , indeed, all that is necessary for that purpose is that at the instant when the winding e of the iron-cored choke-coil is only traversed by the direct current i_g , the corresponding inductive reactance $\omega_1 L$ is equal to the 15 capacitive reactance

$$\frac{1}{\omega_1 C}$$

The shape of the coupling reactance x_k in dependence upon the modulating current i_m is shown in Figure 2, where graph A shows the dependence of the variable reactance $\omega_1 L$ of the iron-cored choke-coil active for the radio frequency and therefore proportional to the differential quotient

$$\frac{dB}{di}$$

of the inductance upon the resultant current i_r . For the point P of the abscissa which corresponds 30 to the direct current i_g , the corresponding ordinate $\omega_1 L$ of graph A equals in amount to

$$\frac{1}{\omega_1 C}$$

35 and in that case the resultant reactance x_k disappears. For positive values of i_m which are plotted on the abscissa axis from point P towards the right-hand side, they are negative, and for negative values positive, as indicated by the line A' passing through point P and equidistant in reference to the curve A. If conditions are so chosen that $\omega_1 L$ is approximately linear between limits $i_g - J_m$ and $i_g + J_m$, then the resultant reactance x_k is substantially proportional to the instantaneous value i_m of the modulating current, and there holds true this equation:

$$x_k = i_m \tan \beta = J_m \sin \omega_m t \cdot \tan \beta \quad (1)$$

40 For the voltage vector E_a at the terminals aa there holds generally this equation:

$$E_a = J_1 \frac{x_k Z}{Z + x_k} \quad (2)$$

45 If impedance vector Z in the numerator is con-

5

10

15

20

30

35

40

45

50

55

siderably larger than x_k , this latter quantity may be disregarded, and the fraction

$$\frac{Z}{Z+x_k}$$

5

may be taken to be equal to unity, and then there is obtained with sufficient closeness and approximation:

$$E_a = J_1 x_k \quad (3)$$

10

It may be noted parenthetically that the approximation will be particularly close if Z , as is recommended, is substantially an active resistance.

15

It will be seen that the amplitude of this potential, if also J_1 is kept at a constant value by suitable means, will not remain constant but is modulated in dependence on x_k at the rhythm of the frequency ω_m . If the coupler branch experiences no appreciable ohmic losses, then its

20

impedance x_k will be practically pure reactance, and the voltage E_a leads the current J_1 by an angle of 90 degrees. The instantaneous value e_a of the voltage will then be:

25

$$e_a = J_1 \sin \left(\omega_1 t + \frac{\pi}{2} \right) x_k = J_1 \cos \omega_1 t \cdot x_k \quad (4)$$

or in the light of Equation (1):

$$e_a = J_1 J_m \tan \beta \cdot \cos \omega_1 t \cdot \sin \omega_m t \quad (5)$$

30

If by the adoption of special means care be taken so that J_1 remains constant regardless of the changes in the coupling reactance x_k then the factors $J_1 J_m \tan \beta$ in the last equation form a constant product $2k$, so that there holds good this formula:

or else,

$$e_a = 2K \sin \omega_m t \cdot \cos \omega_1 t \quad (6)$$

40

The current J_2 set up by the potential E_a in branch Z is:

$$J_2 = \frac{E_a}{Z} = J_1 \frac{x_k}{Z} \quad (8)$$

45

Hence, also the amplitude J_2 , in the presence of constant J_1 and Z is not constant, indeed, it varies conjointly with the factor x_k at the rhythm of the modulating frequency ω_m , in other words, it splits again into two currents having the frequencies $(\omega_1 + \omega_m)$ and $(\omega_1 - \omega_m)$ and equal amplitudes.

50

It will be noted that it is, as matter of fact, possible, by the aid of modulation as described of a radio frequency current i_1 , to obtain two different radio frequency oscillations of the same amplitudes, without obtaining any of the original carrier frequency. In a similar way it would also be feasible, by the superposition (or heterodyning) of several modulating currents, to obtain several pairs of radio frequency in the branch Z , as will be readily understood by introducing in Equation (1) for i_m an expression $\sum J_m \sin \omega_m t$ with different values of m .

65

Hence, if modulation is effected simultaneously, say, at 100, 200, 300, 400 cycles, the result will be several radio frequency currents, which differ from one another by like amounts.

70

It will be noted from what precedes that in a way as disclosed it is possible to split a given radio frequency current into two or more radio frequency oscillations of different frequencies by inserting between the terminals pp and the load branch Z a coupling variable as to size and sense, which, in the course of a period or cycle of the

modulating current, in accordance with the variations of the coupling factor

$$\frac{x_k}{Z}$$

5

occurring in Equation (8) will pass through zero twice and incidentally change or reverse its sense.

In the above derivation the presupposition has been made that it is possible to maintain the amplitude value of i_1 at a constant value independently of variations of the coupling x_k . A simple scheme adapted to insure this is shown in Fig. 3. The current i_1 whose amplitude J_1 is to be kept constant, is taken from an oscillation circuit $L''C''$ which is tuned to resonance with the radio frequency ω_1 , said oscillation circuit in turn being fed with energy from a source qq in loose coupling relationship therewith by way of a coupling coil L' . Owing to such loose coupling, the coil L' suffers practically no reaction at all from the circuit with which it is thus associated, with the result that its current remains constant and that a constant A. C. voltage is induced in the coil L'' . Since the oscillation circuit $L''C''$ is tuned to the frequency of this constant induced potential, the current J_1 , as is well known, will be maintained at a constant value automatically irrespective of all changes of impedance of other connected circuits. The load impedance Z in Fig. 3 consists of the impedance of circuit I including the transferred resistance of amplifier V coupled therewith through circuit II.

What is important is that the ohmic resistance of the coupler branch should be negligibly low, for in that case the coupler circuit, each time that the reactance x_k disappears, represents a perfect short-circuit for impedance Z so that the modulated amplitude of i_2 then passes through the zero value each time and contains no modulated component of the carrier wave ω_1 . Since the losses, when radio frequency currents are dealt with, are primarily occasioned by the iron-cored choke-coil L , it is reduction of the iron losses that should be aimed at in the first place. It is a good plan to employ in lieu of ordinary iron-cored choke-coils, stretched or straight conductors coated with a thin layer of iron of the kind used in radio frequency work for other purposes see, for instance, German patent application No. 447,150. 50

A suitable circuit scheme for this purpose is illustrated in Fig. 4.

As there shown, the coupling branch is divided into two like parallel branches LC , comprising inductances L consisting of straight iron-coated conductors, say, conductors wrapped with a capillary iron wire or covered by electro-plating with a thin film of iron. The direct current i_g and the modulating current i_m are fed at the corners ee , whereas the connections for the radio frequency current i_1 and the modulated radio frequency current i_2 are at points aa . A small variable inductance L_a serves for accurate adjustment.

However, also in this arrangement it is rather difficult to eliminate entirely the influence of the ohmic losses.

In what follows a number of circuit arrangements shall be described wherein the undesirable influence of the ohm or loss resistances is practically precluded entirely or in which these are even put to a practical use.

In the scheme illustrated in Fig. 5, the circuit of the constant radio frequency currents i_1 is coupled with the circuit carrying the modulated radio fre-

75

quency current i_2 by the aid of a Wheatstone bridge a_1a_1 are the terminals for the radio frequency current i_1 and for the modulating current i_m . a_2a_2 are the terminals for the direct current i_g and the modulated radio frequency current i_2 . The variable inductances L_1L_2 may also in this instance consist of ordinary choke-coils or, better still, of the said iron-coated or iron-wire wrapped straight conductors. It is recommendable to choose the condensers C sufficiently large in order that they may constitute no unduly high reactance for the modulating current i_m , and to tune the inductances L_0 together with the condensers C contained in their branches with the modulating frequency ω_m . However, this latter instruction need not be observed absolutely.

It is furthermore not absolutely necessary that the currents i_m and i_1 should be passed through one and the same winding of the choke-coil L as shown in Figure 1, on the contrary, it may be advisable or preferable, inter alia, to provide distinct windings therefor being connected in series in relation to each other, though differentially in relation to the direct current excitation, for the purpose of insuring absolute phase equality of the currents i_m in both limbs.

The operation of the circuit scheme shown in Fig. 5 is as follows:

At the instants when the modulating current i_m is of zero value the two inductances L_1 and L_2 are perfectly equal, and the corner points a_2a_2 are equipotential as regards the radio frequency ω_1 so that i_2 will also disappear. During a half cycle of the modulating frequency ω_m the modulating current i_m in one of the variable inductances, for instance, in inductance L_1 is unidirectional with the direct current, and in limb L_2 opposite in direction to the direct current so that the inductance of the first limb is lower than in the second. During the next half cycle this relationship of the inductances is inverted. Hence, if at a definite instantaneous value and direction of i_1 and i_m the modulated radio frequency current i_2 has a corresponding instantaneous value and a corresponding sense, then after a half cycle of the modulating frequency (if current i_1 has the same size and direction as before, and current i_m the same instantaneous value, though contrary sense) for the current i_2 the same instantaneous value as before, though of opposite sense. Currents i_2 and i_1 are associated by the relation $i_2 = i_1 \times f(i_m)$ where the function $f(i_m)$ can be regarded and designated as "coupling factor". This coupling factor passes simultaneously with i_m through zero and it changes its sign together with i_m , hence, it is a periodical quantity substantially proportional to i_m having a frequency of variation (ω_m), whence the inference that the current i_2 is a purely modulated radio frequency current, in which there occur no unmodulated remnants of the carrier frequency.

Calculating for a Wheatstone bridge comprising arm impedances a_1 , a_2 , a_3 , a_4 (Fig. 6) the coupling factor, i. e., the ratio between the diagonal currents $J_2:J_1$, there is found this relation:

$$J_2 = J_1 \frac{a_1 a_3 - a_1 a_4}{Z(a_1 + a_2 + a_3 + a_4) + (a_1 + a_2)(a_3 + a_4)} \quad (9)$$

Now, suppose that impedances a_3 and a_4 correspond to arms L_0C_0 , Fig. 5 and impedances a_1 and a_2 to arms L_1 and L_2 , Fig. 5. Then a_3 and a_4 are permanently alike, and a_1 and a_2 , if i_m dis-

appears, assume both the value a , otherwise the amplitude:

$$a_1 = a + \Delta a = a + K - i_m \quad (10)$$

and

$$a_2 = a - \Delta a = a - K - i_m \quad 5$$

where Δa denotes the vectorial component of the impedances a_1 and a_2 , respectively, which is due to the current i_m ; and K is a factor of proportionality.

(In this case the variation factor a may contain both the reactance variation as well as the variation of the loss resistance). Then the sum total:

$$a_2 + a_1 = a + K i_m + a - K i_m = 2a \quad (10a) \quad 15$$

is independent of the modulating current, hence, the denominator Equation (9) remains constant. The numerator, however, becomes equal to

$$a_3(a_1 - a_2) = 2a_3\Delta a = 2aK i_m \quad 20$$

so that the Equation (9) assumes this form

$$J_2 = J_1 K i_m \quad (11)$$

where K a constant. What follows therefrom is the fact that J_2 is modulated at the rhythm of current i_m perfectly, in the absence of any trace of the original carrier frequency.

In the scheme shown in Fig. 5, both arms have constant reactances, it being understood, of course, that all of the four arms could consist of variable reactances controllable by the modulating current. In this instance, opposite reactances must always change in the same sense, i. e., reactances a_2 and a_4 , see Fig. 6, in the presence of a certain direction of the modulating current, must both grow, and the reactances a_1 and a_3 both decrease, and vice versa.

In all of the embodiments hereinbefore described, recourse has been had to the superposition of a direct current and a modulating current. However, this is not absolutely necessary, indeed, the schemes hereinafter to be described by reference to Figs. 7 to 10 are not in need of direct current.

In the arrangement shown in Fig. 7, the inductance of arm L_2 is subject to marked variations as a function of the modulating current i_m . However, the inductance of arm L_1 is subject to but slight change, indeed, it should most preferably be entirely constant for instance, when L_1 is an air-core choke-coil. To compensate for the load resistance, a small variable ohm resistance is connected in series with the choke-coil L . The two choke-coils L_2 and L_1 are so chosen that, in the presence of a certain mean absolute value of the modulating current i_m the inductance of the choke-coil L_2 for radio frequency current i_1 is equal to the inductance L_1 . But if the absolute value falls below the average, then L_2 becomes smaller than L_1 . Hence, also in this arrangement the coupling factor, similarly as in the preceding embodiment, is a periodic function. However, in this instance it passes through zero four times during a cycle of the modulating current and incidentally changes in sense or sign, with the result that current i_2 is here modulated by the frequency of $2\omega_m$.

In the scheme shown in Fig. 8 the two inductances L_1 L_2 consist of two transformers having their secondaries connected in opposition. The mutual inductance of the iron-cored transformer L_2 , in the presence of a definite mean absolute value of i_m is here equal to the mutual inductance

of transformer L_1 , the latter again being but little variable or most preferably constant.

If the transformer L_1 is entirely free from iron, it is advisable to provide in parallel thereto a variable resistance radio frequency for the purpose of compensating the iron losses of the other transformer.

Also in this case the effects of the two transformers upon the secondary circuit compensated 10 each other at the instant when the modulating current i_m passes through the above-mentioned mean value. In the presence of larger absolute values of the modulating current, the action of L_1 predominates, and for lower values of the modulating current, the action of L_2 will prevail, so that the modulating effect is here the same as in the previous scheme.

Another means and way of modulation resides 20 in the use of condensers of well-known type comprising one or two movable or vibratory electrodes.

The arrangement in Fig. 9 shows the use of such a condenser. In this instance, the coupling branch consists of a constant inductance and a 25 condenser furnished with one vibratory electrode. This scheme resembles the one illustrated in Fig. 1. The distinctive feature between the two resides in that the resultant coupling reactance x_k is controlled not by the co-action of a direct current and the modulating current, but rather by the vibratory electrode of condenser C. The two parts of the coupling branch are here so chosen that in case of a median position of the vibratory electrode the inductive reactance of the choke-coil and the capacitive reactance of condenser C neutralize each other so that the coupling reactance x_k disappears. In the presence 30 of smaller inter-electrodes distances x_k becomes inductive and at larger distances capacitive. Hence, also in this instance the coupling reactance reverses in sign, and this results in modulation of current i_2 at the rhythm of the oscillations of the vibratory electrode.

45 Another similar arrangement is shown in Fig. 10. In this case the coupling between circuits i_1 and i_2 is provided by a Wheatstone bridge, here comprising four condensers C_1, C_2, C_3, C_4 . One among the latter, e. g., C_1 is furnished with a vibratory electrode, and when the latter occupies a median position, the bridge is in a balanced condition and current i_2 disappears. Larger inter-electrode distance result in a definite sense 50 of coupling, while smaller distances cause the opposite condition. The operation of this scheme will be readily understood in the light of what has been explained above.

In case of a bridge arrangement, as will be 60 understood, choke-coils could be employed instead of condensers in two neighboring limbs or bridge arms. Also condensers furnished with vibratory electrodes could be employed in two arms. For instance, if arms C_1 and C_2 were so provided, then the vibratory electrodes would be compelled 65 to oscillate in phase opposition, while they would oscillate in phase if they were contained, for instance, in the arms C_1 and C_2 .

70 It may also be mentioned that in so far as the operation of the bridge schemes hereinbefore described is concerned, all that is important is that at least in one arm a resistance be modulated, and that the other arms should be so compensated or balanced that the bridge is balanced 75

when the said modulated resistance has a median value.

Hence, the desired result can also be obtained if instead of the vibratory-electrode condensers, tube resistances of well-known type responsive to 8 or influenced by modulation are used, and if the resistances of the other arms are chosen correspondingly.

It may be noted in conclusion that in explaining the operation of several bridge schemes (Figs. 10 5, 5a, 7 and 10) the assumption has been made for the sake of simplicity that the variable reactance when being of median value, becomes equal to another reactance, though this is not absolutely necessary. Indeed, it suffices that the 15 bridge arrangement should be so proportioned that, in the presence of mean values of the resistances contained therein, proportional relationship between the four arms of the bridge should be present as required for a balanced state of 20 the bridge. However, the sensitivity of the scheme will be the highest when the relation between the arm resistances is equal.

We claim:

1. In an arrangement for producing a plural- 25 ity of radio frequency waves for transmission from a source of high frequency oscillations which are to be suppressed, a transmission line adapted to be connected to said source, a circuit connected across said line, said circuit directly including 30 at least two reactances of opposite sign, one of which is adapted to be varied by modulating currents about a mean value, said reactances being normally resonant at the carrier frequency, means for impressing modulating currents across only 35 one of said reactances, output terminals for said circuit, and utilizing means connected to said output terminals.

2. In an arrangement for producing a plural- 40 ity of radio frequency waves from a source of high frequency oscillations which are to be simultaneously suppressed, a circuit connected in parallel with said source, said circuit including a capacitive reactance and an inductive reactance which are normally resonant at the carrier frequency, a 45 source of biasing current and a source of low frequency modulating current coupled with one of said reactances, said reactance being varied by the modulating currents about a mean value twice per cycle of said low frequency modulating 50 current, and a load circuit connected with said circuit, said one reactance having an inductive reactance equal to the capacitive reactance in the absence of modulating current.

3. In an arrangement for producing a plural- 55 ity of high frequency waves by means of a carrier wave which is to be suppressed, a circuit including series reactances of opposite sign, one of said reactances being an iron core inductance, 60 means for applying said carrier wave to the terminals of said circuit, a magnetizing winding on said core, a source of direct current connected with said winding, said circuit being normally resonant at the frequency of said carrier wave, and means for impressing modulating currents 65 across said iron core inductance.

4. Means for producing a plurality of signal modulated radio frequency waves from a source of carrier frequency which is simultaneously suppressed, including a bridge circuit the arms of 70 which are composed entirely of reactances, one of said reactances being arranged to vary in value about a mean value, means for impressing carrier frequency oscillations across a pair of conjugate 75

5 nodal points on said bridge, a source of direct current, means for connecting said source of direct current across another pair of conjugate nodal points on said bridge circuit, a source of 5 modulating current, means for connecting said source of modulating current across said first named pair of nodal points, said modulating current being connected differentially with respect to said direct current, and a load circuit connected to said bridge circuit.

10 5. In an arrangement for producing substantially equal side band frequencies from a source of carrier frequency and simultaneously suppressing said carrier frequency, a plurality of 15 reactances connected in series with said source, two of said reactances being of opposite sign, said reactances being normally resonant at signal frequency, means for applying a modulating current across only one of said reactances such that the 20 value of said reactance varies about a mean point, and a load circuit connected with said reactances.

25 6. Apparatus for producing a plurality of signal modulated radio frequency waves from a source of carrier frequency which is to be suppressed comprising a bridge circuit the four arms of

which are composed entirely of reactances, one of said reactances being arranged to vary in value about a mean value, a source of carrier frequency oscillations across a diagonal of said bridge, a source of direct current serially connected with 5 an inductance across the other diagonal of said bridge, a source of modulating current also connected across said first named diagonal, and a load circuit connected across said second named diagonal.

10 7. Apparatus for producing a plurality of signal modulated radio frequency waves from a source of carrier frequency which is to be suppressed comprising a bridge circuit, the four arms of which 15 are composed entirely of reactances, a source of carrier frequency oscillations connected across one diagonal of said bridge, an additional reactance in series in said connection, a source of direct current and a source of modulating current 20 connected in parallel across the other diagonal of said bridge, and a load circuit connected in series with said additional reactance across said first diagonal.
